UNITED STATES PATENT OFFICE.

WALTER THOMPSON, OF CHESTER, PENNSYLVANIA.

PISTON PACKING-RING.

1,031,744.

Specification of Letters Patent.

Patented July 9, 1912.

Application filed June 10, 1911. Serial No. 632,383.

To all whom it may concern:

Be it known that I, WALTER THOMPSON, a citizen of the United States, residing at Chester, in the county of Delaware and State of Pennsylvania, have invented certain new and useful Improvements in Piston Packing-Rings, of which the following is a specification, reference being had to the accompanying drawings.

This invention relates to packing rings for pistons and more particularly to packing rings of that character made up of a plurality of segments independently movable circumferentially and radially with respect to the piston, the present invention having for its principal object the provision of such ring sections so constructed and mounted in the piston as to absolutely prevent leakage around the periphery of the cylinder.

A further object of the invention resides in the provision of a plurality of packing ring sections of the above described character, the opposed ends of adjacent sections having sliding movement upon each other and upon the walls of the annular groove or channel in the piston head in which said ring sections are seated.

A further object of the invention is to provide improved means for mounting the ring sections in the piston head, and guiding the same in their radial movement.

With the above and other objects in view, the invention consists of the novel features of construction, combination and arrangement of parts hereinafter fully described and claimed, and illustrated in the accompanying drawings, in which—

Figure 1 is a side elevation of a piston showing two of my improved segmental packing rings arranged therein; Fig. 2 is an enlarged section taken on the line 2—2 of Fig. 1; Fig. 3 is a section taken on the line 3—3 of Fig. 2; and Fig. 4 is a detail perspective view of one of the ring segments.

Referring in detail to the drawing 5 designates the piston head which is preferably constructed from brass or other suitable metal and is provided with one or more 50 annular grooves or channels 6. Radially extending cylindrical recesses or sockets 7 are formed in said head at diametrically opposite points and open into the channel 6.

Within the channel 6 of the piston head, 55 a plurality of ring segments 8 are movably arranged, said segments being also con-

structed from brass or other desired metal, each of said ring segments describing substantially one-quarter of a circle. The convex faces of said segments lie in the same 60 plane as the periphery of the piston head when the segments are wholly disposed within the annular channel or groove 6. Each of the packing ring sections is made up of a body bar 9 which is of substantially 65 inverted T-shape form and the longitudinal side strips 10 which are arranged upon the laterally extending base flanges 9¹ of the body bar. These side strips are securely riveted to the body bar as indicated at 11 70 and one of their ends is extended beyond one end of the body bar as at 12 whereby said strips provide a short longitudinal recess 13 between their opposed faces. The other ends of the strips 10 terminate in 75 advance of the opposite end of the body bar so as to provide the recesses 14 on opposite sides of the vertical portions of the inverted T-shaped body bar which receive the projecting ends 12 of the side 80 strips 10 on the opposed end of the adjacent ring section. To the concave face of the body bar 9, a stud or cylindrical pin 15 is secured, said pin being formed adjacent its attached end with an annular enlargement or shoulder 16. In the cylindrical recesses or sockets 7 of the piston head the coiled springs 17 are arranged, and these springs are adapted to loosely receive the pins 15 carried by the ring segments, the 90 outer ends of said springs engaging the annular shoulders 16 of said pins and normally acting to force the ring segments outwardly beyond the periphery of the piston head. 95

From reference to Fig. 3, wherein the packing ring segments are shown in the positions they would occupy when the piston is working in its cylinder, it will be observed that the extending end portions 12 100 of the metallic side strips 10 of the ring segments engage closely upon the base flanges 11 of the adjacent ring segment, and are adapted to slide thereon circumferentially in the reciprocation of the piston so as to 105 reduce to a minimum the friction induced between said ring segments and the wall of the piston cylinder. It will also be noted that the projecting ends 12 of the side strips 10 substantially entirely fill the space 110 between the opposed walls of the groove or channel 6 of the cylinder head and the op-

posite sides of the vertical portion of the body bar 9 which provides the recesses 13 in which the ends of said strips are received. This interfitting engagement of the opposed 5 ends of the ring segments will effectually prevent the escape of steam, gases or other actuating fluid around the periphery of the piston, and as the cylinder wears, the ring segments are forced outwardly and held in 10 close engagement therewith by means of the springs 17 arranged in the cylinder head. In the event that the side strips 10 of any one of the sections should become so far 15 worn as to ineffectually perform their function of preventing leakage around the packing ring, said side strips may be readily removed and replaced by new ones. Thus a 20 perfectly tight non-leaking packing ring is provided, the efficiency of which may be indefinitely maintained at a very slight expense.

From the foregoing it is thought that the construction and operation of my improved 25 metallic packing ring will be properly understood.

While the device is primarily devised for use in connection with gas engines, it will 30 of course be understood that it is not limited to such use but may be employed in connection with reciprocating pistons such as are used for a great many different purposes.

If desired the packing ring sections may 35 be formed from a harder metal than that of the piston head itself so that the use of the piston can be continued even after the same becomes so far worn that it could not be employed without the use of a packing of

the character above set forth. It will also be obvious that the device is susceptible of 40 a great many other minor modifications in form and proportion without departing from the essential feature or sacrificing any of the advantages of the invention.

Having thus described the invention what 45 is claimed is:-

A device of the character described, a piston having a plurality of annular rectangular grooves formed therein, a ring mounted in each of said grooves comprising 50 a plurality of spaced arcuate sections, a plurality of radially extending cylindrical sockets mounted in said piston and communicating with said grooves, each of said arcuate sections consisting of a substantially 55 inverted T-shaped bar, arcuate side strips seated upon the lateral flanges of the sections of said ring and permanently secured adjacent the ends thereof, cylindrical pins mounted for reciprocation within said 60 sockets, a shoulder formed on said pins and integral therewith, a reduced portion extending from said shoulder, the center portion of said arcuate sections being permanently secured to said reduced portions of 65 said pins, coil springs mounted within said sockets and the said annular shoulder adapted to retain said coil springs within said sockets substantially as and for the purpose described.

In testimony whereof I hereunto affix my signature in the presence of two witnesses.

WALTER THOMPSON.
